UNITED STATES PATENT OFFICE.

GEORGE GRAFF, OF NEW YORK, N. Y., ASSIGNOR TO GRAFF, WASHBOURNE & DUNN, A CORPORATION OF NEW YORK.

DESIGN FOR A CLOCK LAMP.

Application filed February 8, 1921. Serial No. 443,472. Term of patent 14 years.

To all whom it may concern:

Be it known that I, GEORGE GRAFF, a citizen of the United States, residing at New York city, county of Bronx, State of New York, have invented a new, original, and ornamental Design for a Clock Lamp, of which the following is a specification.

This invention relates to a new, original, and ornamental design for a clock lamp, and the invention consists in the peculiar shape of the same, substantially as shown in the accompanying drawing, forming a part of this

specification, in which the figure is an elevation.

The design consists in the peculiar shape of the device with the base A, standard B of narrower diameter, and bell shaped dial carrier or shade C.

I claim.

The ornamental design for a clock lamp, as shown and described.

In testimony whereof, I have hereunto set my hand.

GEORGE GRAFF.
